(57) **CLAIM**

The ornamental design for a device interface, as shown and described.

DESCRIPTION

FIG. 1 is a right-front perspective view of a device interface showing the new design; and,
FIG. 2 is a top view thereof.

The broken lines showing in FIG. 1 are for illustrative purposes only and form no part of the claimed invention.

1 Claim, 2 Drawing Sheets

FIG. 1

FIG. 2
